NEEDLE THREADING DEVICE

Rex I. Bissell, Willamina, Oreg.

Application December 10, 1937, Serial No. 179,195

1 Claim. (Cl. 223—99)

The object of my present invention is the provision of a simple, inexpensive, and useful needle threading device.

To the attainment of the foregoing the invention consists in the improvement as hereinafter described and definitely claimed.

In the drawing, accompanying and forming part of this specification:

Figure 1 is a view partly in elevation and partly in section of one embodiment of my invention.

Figure 2 is an end elevation of the same.

Figure 3 is a plan view of a modification.

Figure 4 is a detail view taken substantially on the line 4—4 of Figure 3.

Referring first to Figures 1 and 2 of the drawing it will be noted that the device comprises a wooden member in the form of a spool and designated by the reference character 10. The member of spool form 10 is flanged at its ends 11, and in one flange 11 is provided a radial notch or recess 12 which extends to the periphery of the flange and between the inner and outer sides thereof and is closed at its bottom or end nearest to the longitudinal center or axis of the member.

A hook 13 has the heel end of its shank embedded and fixed in the fibrous material of the spool form member so that it extends radially from the bottom wall of the recess 12 and so that its bill or head is adjacent to the periphery of the flange 11 though entirely within the recess 12 so as to offer no projection whatsoever from the member 10.

In the modification shown in Figures 3 and 4

the recess is designated by the reference numeral 12a and is essentially of U-shape in cross section being open at one side, and the open side being at the periphery of the flange. Also, the shank of the hook 13 is driven or otherwise embedded in the wood of the member 10a with the hook extending into the recess 12a but not beyond the same.

To thread a needle, one end of the thread is passed around the end of the hook 13 after the end of the hook has been passed through the eye of the needle. With the end of the thread thus looped about the hook and above the eye of the needle it will be obvious that upon removal of the needle from the hook the looped portion of the thread will pass through the eye of the needle thus threading the needle. As the end of the thread passes through the eye of the needle, the thread may be drawn through the eye of the needle to the desired extent.

Having described my invention what I claim and desire to secure by Letters Patent, is:

A needle threading device comprising an elongated handle forming member of fibrous material having a flange of substantially cylindrical shape at one end thereof, said flange having a notch in the peripheral portion thereof which passes through the inner and outer faces of the flange, said notch having a straight bottom wall, a shank having one end portion embedded in the straight wall and having a barb at its free end, said shank and barb being located within the recess.

REX I. BISSELL,
